CLAIM

The ornamental design for a positive airway pressure delivery console, as shown and described.

DESCRIPTION

FIG. 1 is an exploded front view of a positive airway pressure delivery console showing a first embodiment according to our new ornamental design;

FIG. 2 is a rear view thereof;

FIG. 3 is a top view thereof;

FIG. 4 is a bottom view thereof;

FIG. 5 is a right side view thereof;
FIG. 6 is a left side view thereof;
FIG. 7 is a sectional view along line 7-7 of FIG. 1;
FIG. 8 is a sectional view along line 8-8 of FIG. 2;
FIG. 9 is an exploded front view of a positive airway pressure delivery console showing a second embodiment according to our new ornamental design;
FIG. 10 is a rear view thereof;
FIG. 11 is a top view thereof;
FIG. 12 is a bottom view thereof;
FIG. 13 is a right side view thereof;
FIG. 14 is a left side view thereof;
FIG. 15 is a sectional view along line 15-15 of FIG. 9; and,
FIG. 16 is a sectional view along line 16-16 of FIG. 10.
The broken lines represent environment or structure and do not form a portion of the claimed design.
One or more views (e.g., the bottom view) may be omitted and therefore does not form a part of the claimed design.
